Attorney

UNITED STATES PATENT OFFICE.

SIDNEY C. VINCENT, OF BALTIMORE, MARYLAND.

GAS BURNER.

Application filed August 19, 1925. Serial No. 51,139.

This invention relates to a gas burner, and more especially it relates to such a burner intended to heat a steam drum for generating steam to be mixed with oil for furnace heating, although as will be seen, it is admirably adapted for steam generation for other purposes.

The primary object of the invention is to make the burner mechanism automatic in its action, that is to say, it embodies a construction in which the gas is cut off, and consequently the flame is extinguished, and the gas re-lighted according to the exigencies and requirements of use.

15 A further object is to so construct the mechanism that it will be durable and simple in construction and not likely to get out of order and be reliable and dependable in operation.

20 A still further object of the invention is to so construct the mechanism that the consumption of gas will be reduced to a minimum which obviously results from the fact that the gas is entirely cut off from the burner 25 when the burner is in its lowermost position, or the position in which its flame is not needed for the generation of steam.

In the drawings—

Fig. 1 is a view somewhat diagrammatic or 30 schematic in character, showing the burner in raised or operative position below the steam drum, there being shown in dotted lines, the lowermost position or that in which the gas flame is extinguished.

35 Fig. 2 is a plan view of the gas cock partially in section.

Fig. 3 is a cross section taken about on line *a—a* of Fig. 2.

40 Fig. 4 is a central section of the nozzle at which is maintained the furnace heating flame.

Referring to the drawings, the numeral 1 designates the steam drum that may be of any approved construction, but preferably 45 of flattened ovoid shape, as shown. This contains a steam coil 2 having small perforations 3 therein. To the lower portion of the drum is connected a vertical steam pipe 4 which has its lower end let into the nozzle 5, which 50 nozzle will later be described in detail.

Connected to the lower end of the nozzle is an oil pipe 7 leading to any suitable source of oil supply, and as will later appear, the action of the steam from the steam drum issuing 55 through the nozzle, which is specially con-

structed, will act as an injector to draw the oil into the nozzle to be therein mixed with the steam and air, which mixture is ignited at the nozzle to maintain an intense heat within the furnace, for instance, the mixture constituting a fuel to take the place of coal or other combustible material commonly used in furnaces.

The more important part of my invention which I now stress has to do with the burner mechanism. The numeral 8 designates the gas cock, and by reference to Fig. 2 this will be seen to be constituted by a base 9 for attachment to any suitable support and a short upright or standard 10 which terminates in 70 a laterally extending conical key 11 surrounded by a snugly fitting rotatable body or sleeve 12. This sleeve is provided on one side with an apertured internally threaded boss 13, the aperture being virtually a continuation of the hole 14 in the sleeve, which hole at times is adapted to register with a port 15 in the wall of the key, which port communicates with a chamber 16 in said key.

Threaded into the key and opening in said chamber is the nipple 17 upon which is threaded the **T** connection 18, to which in turn is connected in the usual way the gas inlet pipe 19 communicating with the house main, or other source of gas supply. Threaded into the **T** and communicating with the gas source is a pilot burner 20 whose open outer end extends into close proximity to the nozzle 5, as clearly shown in the main figure, so as will presently appear, it will always be in position to re-ignite the vapor at the nozzle when necessary or desirable in the operation of the mechanism. This pilot burner, as just intimated, is maintained constantly throughout the entire time in which it is desired to bring about automatic operations of the mechanism.

Threaded into the threaded opening in the boss 13 is the burner tube 21, which is bent at its outer end to form a circular burner 22 having in the top thereof a series of properly spaced and sized holes 23 in position to direct the flame against the bottom of the steam drum, the circular formation of the burner permitting it to surround the steam pipe 4 leading from the drum to the nozzle. Preferably I arrange the holes in the burner at an angle so that when it is in raised position under the drum, the flame will be directed in true vertical direction because when 110

the burner is in raised position, it is the only time that the gas cock is open and that the flame is extant.

On the side of the sleeve opposite the burner tube is an arm 24 bifurcated as indicated at 25 for the reception of the upper end of a short link 26 which is pivoted in the bifurcation as shown. The lower end of the link is pivoted at 27 in a similar bifurcation in 10 the upper end of a piston rod 28 which extends through a properly packed stuffing box 29 formed in a cap 30 which closes the upper end of a steam cylinder 31, the rod being provided with a piston 32. The lower 15 end of the cylinder is closed by a cap 33 into the bottom of which is threaded a short pipe 34 having a branch 35 connected with a steam pipe 36, which in connection with the nozzle will be presently described. The 20 cap 33 at the bottom of the cylinder is provided with a flange 38 to which are attached the lower ends of two spiral springs 39 whose upper ends are attached to a cross bar 40 carried by the piston rod, the springs exerting 25 their force to bring the piston to its lowermost position in the cylinder, thereby raising the burner and opening the gas cock.

The water supply in the steam drum may be regulated by a suitable thermostat operating through a rod *a* upon a suitable valve *b*. This thermostat operates to supply water to the coil when necessary, and since the burner is operated by steam pressure, as will later appear, through the cylinder and its connections with the burner, there will be no steam when there is no water, but the drum will be in a highly heated condition due to the fact that the burner will be in raised position and the cock open and in readiness to generate steam immediately the thermostat actuates the valve governing the water supply to the coil.

The key of the burner, it will be observed, is somewhat like the key in an ordinary gas fixture except in the present instance, it is differently chambered and there is provided as indicated at 41 the usual nut for drawing the key into the sleeve to bring about the necessary tight fit between the key and body.

Referring particularly to Fig. 4, it will be noted that the nozzle 5 is of shell formation, and as shown is preferably conical. It has a flame orifice 6 communicating with a chamber A. In this chamber is a core B somewhat smaller than the chamber and shaped like the chamber, so that a space C will be left between the walls of the shell and the core. The core is chambered as indicated at D, communicating with this chamber is a pipe E, which with the chamber D virtually forms a continuation of the steam pipe 4. Extending upwardly from the chamber D to the space around the core are a series of perforations F, the purposes of 65 which will be presently described.

The bottom of the nozzle is provided with a series of perforations G, annularly arranged, and which communicate with the interior of the nozzle. These are for the admission of air into the nozzle in the operation of the device. Let into the bottom of the nozzle is an oil supply pipe 7 leading to any suitable source of oil supply, and it will be noted that the pipe E extends centrally through the pipe 7 and passes therefrom. The pipe E extends some distance beyond the oil pipe and is fitted with a T to which is connected as shown, the pipe 36 through which steam passes to the cylinder through the branch 35 as shown, the branch 80 pipe being located just above the drain cock 36'. I preferably extend the pipe E beyond its connection with the pipe 36 and provide the extension which is designated by H with a gauge I and the lower end of the pipe H 85 is preferably provided with a trap J.

In operation water is supplied to the coil 2 and with the parts as shown in the position in full lines in the main figure, the ports in the sleeve and key will be in registry and the gas turned on. At the start the burner and pilot are lighted with a match, the dome heated and water turned on. If the dome is well heated, formation of steam is almost instantaneous, and the steam passes through the steam pipe 4, into the nozzle 5 in which it is mixed with the oil and air and sprayed into the zone that it is desired to heat. The steam passing into the core B is divided, part passing into the pipe E and part deflected through the perforations F toward the top of the nozzle. The portion of the steam whose direction is reversed and caused to pass through said perforations acts as an injector to draw the oil or oil vapor into the nozzle for ignition at the top of the nozzle. At the same time by the same injector force air is drawn into the nozzle through the perforations G so that there is a mixture in the nozzle of steam, oil, or oil vapor and air, which when ignited maintains, as is obvious, an intense heat with perfect combustion. When the pressure of the steam which quickly rises has reached a certain point the piston in cylinder 31 will be raised through the link 26 and arm 24, thus rocking the sleeve until the ports in the sleeve and key are out of registry when obviously the gas will be cut off. So long as this closing pressure is maintained in the cylinder throughout the operation of the mechanism, the burner will be maintained at its lowermost position adjacent the pilot burner and nozzle, but since the pressure falls in the cylinder the springs 39 will draw the cylinder to its lowermost position, raising the burner to position to generate steam in the drum, the burner being re-lighted by the dying flame above the nozzle.

Claims:

1. In a gas burner, in combination, a sta-

- tionary chambered key having a port therein, a sleeve surrounding said key and movable circumferentially of said key, said sleeve being also provided with a port adapted to register with the port in the key, means for supplying gas to said key, a burner carried by the sleeve and communicating with the port therein, means for automatically rocking the sleeve to open or close the ports to permit gas to be supplied to the burner or shut off therefrom. 40
5. In a gas burner, in combination, a stationary chambered and ported key, a ported sleeve surrounding said key and adapted to move circumferentially of said key, a gas burner secured to the sleeve and adapted to be supplied at times through said ports, means for actuating the sleeve to open and close the ports and consequently control the 15 flow of gas to the burner. 55
6. In a mechanism of the character described, in combination, a steam generator, a gas burner rockable toward and from said generator, means for supplying gas to the burner when said burner is in its closed position to the generator, and steam actuated 60 means for rocking the burner. 60
7. In a mechanism of the character described, in combination, a steam generator rockable toward and from said generator for the purpose set forth, means for supplying 65 gas to the burner when it is in closest position to the generator, said means comprising a piston and cylinder, and steam connections between the generator and said cylinder, and means for holding the piston in its lowermost position in the cylinder in the absence of steam pressure in said cylinder. 70
8. In a mechanism of the character described, in combination, a steam generator rockable toward and from said generator for the purpose set forth, means for supplying 75 gas to the burner when it is in closest position to the generator, said means comprising a piston and cylinder, and steam connections between the generator and said cylinder, means for holding the piston in its lowermost position in the cylinder in the absence of steam pressure in said cylinder, and means 80 for relighting the burner as it is moved toward the generator. 85
4. A gas burner comprising a stationary chambered key, a gas inlet pipe connected with said chamber, a rockable sleeve surrounding the key, both the key and the sleeve 35 having ports therein adapted at times to register, a burner carried by the sleeve and adapted to be supplied through said ports when said ports are in registry, and means for rocking said sleeve. 85
5. In a device of the character described, in combination, a steam generator, a gas cock comprising a chambered and ported key, a sleeve rockable on said key and provided with a port adapted to register with the port in

the key, a gas burner carried by the sleeve and adapted to be supplied with gas when the ports are in registry, connections between the steam generator and the sleeve whereby steam generated in the generator by the burner will operate the sleeve to raise or lower the burner with relation to the generator, and control the admission of gas to the burner, and means for supplying gas to the gas cock. 40

5. In a mechanism of the character described, in combination, a steam generator, a gas burner rockable toward and from said generator, means for supplying gas to the burner when said burner is in its closed position to the generator, and steam actuated 60 means for rocking the burner. 60

7. In a mechanism of the character described, in combination, a steam generator rockable toward and from said generator for the purpose set forth, means for supplying 65 gas to the burner when it is in closest position to the generator, said means comprising a piston and cylinder, and steam connections between the generator and said cylinder, and means for holding the piston in its lowermost position in the cylinder in the absence of steam pressure in said cylinder. 70

8. In a mechanism of the character described, in combination, a steam generator rockable toward and from said generator for the purpose set forth, means for supplying 75 gas to the burner when it is in closest position to the generator, said means comprising a piston and cylinder, and steam connections between the generator and said cylinder, means for holding the piston in its lowermost position in the cylinder in the absence of steam pressure in said cylinder, and means 80 for relighting the burner as it is moved toward the generator. 85

In testimony whereof I affix my signature.

SIDNEY C. VINCENT.
